United States Patent Office.

ISAAC R. BARBOUR, DECEASED, OF HANNIBAL, MISSOURI; WILLIAM G. BARBOUR, ADMINISTRATOR.

Letters Patent No. 92,562, dated July 13, 1869.

IMPROVEMENT IN FURNACE-GRATES.

The Schedule referred to in these Letters Patent and making part of the same.

To all whom it may concern:

Be it known that I, ISAAC R. BARBOUR, of Hannibal, in the county of Marion, State of Missouri, have invented a new and useful Improvement in Furnace-Grates; and I do hereby declare the following to be a full, clear, and exact description thereof, which will enable those skilled in the art to make and use the same, reference being had to the accompanying drawing, forming part of this specification, in which drawing—

Figure 1 represents a plan or top view of this invention.

Figure 2 is a longitudinal vertical section of the same.

Similar letters indicate corresponding parts.

This invention relates to a grate, which is particularly designed for burning shale or slate charged with hydrocarbon-oils, and inferior cannel or other coals, the earthly constituents of which are large, in proportion to the combustible constituents.

My grate is constructed of an upper and lower part, the lower part forming the main grate, and the upper part the cut-off or supporting grate.

The main grate is constructed of two comb-shaped sections, which are hung on pivots or gudgeons at their outer edges, and geared together, by toothed segments or other mechanism, in such a manner that they can be conveniently turned down or agitated by the action of one lever, for the purpose of dumping or stirring up the fire.

When the two sections are turned up, the ends of their grate-bars or teeth overlap each other, whereby the operation of shaking up or agitating the fire is materially facilitated.

The upper or cut-off grate is secured to a sliding carriage, and it is so arranged that it can be pushed in over the main grate, for the purpose of supporting the upper portion of the fuel, while the ashes and slags, which, from time to time, accumulate on the main grate, are dumped.

The main grate can be raised or lowered, so that the space between the same and the cut-off grate can be adjusted according to the nature of the fuel to be burned.

A represents a fire-place of a furnace, into which is fitted the main grate B.

This grate is composed of two comb-shaped sections, which are hung on gudgeons, a, at their opposite edges, so that they open and close in the centre.

The two sections are geared together by toothed segments, b, or in any other desirable manner; and to one of the gudgeons a is secured a hand-lever, c,

which serves to agitate the grate, or to turn the sections down, for the purpose of dumping the ashes and slags.

The teeth of the two sections of the main grate overlap each other, as shown in fig. 1, so that when these sections are agitated, the slags or coals are prevented from catching between said teeth.

One of the side walls of the fire-place is perforated with a series of holes, to admit the prongs of the secondary or cut-off grate C.

This grate rests on a suitable guide-frame, D, and a reciprocating motion can be imparted to it by a lever, E, or in any other desirable manner.

If desired, this cut-off grate may be made in two sections, each of which has a distinct reciprocating motion; and its motion may be facilitated by placing it on wheels or friction-rollers.

By means of this cut-off grate, I am enabled to burn, successfully, such fuel as shale, slate, or inferior coal containing an excess of earthy or non-combustible constituents. If such fuel is burned on an ordinary grate, a large quantity of ashes and slags accumulates on said grate in a short time; and, if these slags are dumped, the whole fire goes out, and has to be renewed. This disadvantage is obviated by my cut-off grate.

When the main grate becomes clogged, I push the cut-off grate directly through the ignited mass, open the main grate, thereby dumping its contents; then replace this grate, withdraw the sliding grate, and that movement throws down the ignited mass to the lower grate; put on a fresh supply of fuel, and so go on.

In order to carry out this operation with different kinds of fuel, it is desirable to adjust the space between the main grate and the cut-off grate. This object is effected by placing the gudgeons of the main grate into slots g, so that said grate can be raised or lowered, as the nature of the fuel to be burned may require.

Having thus described my invention,

What I claim as new, and desire to secure by Letters Patent, is—

1. The combination of the cut-off grate C and main grate B, substantially as set forth.
2. The slotted bearings, g, of the gudgeons of the main grate, substantially as and for the purpose set forth.

ISAAC R. BARBOUR.
